UNITED STATES PATENT OFFICE.

GEORGE A. HULL, OF CHICAGO, ILLINOIS, ASSIGNOR TO EQUIPMENT SPECIALTIES CO., OF CHICAGO, ILLINOIS, A CORPORATION OF ILLINOIS.

REFRIGERATOR CAR.

Application filed March 14, 1927. Serial No. 175,401.

My invention relates to improvements in refrigerator cars, being more particularly concerned with the construction of ventilating openings in metal sections of refrigerator car bulkheads.

In the construction of a burglar proof bulkhead having metal sections, it is very essential that a sufficient area of ventilating openings be provided so that sufficient air may circulate to keep the contents of the car cool under all conditions. Shipments of bananas present particular difficulty in this regard as bananas spoil more easily than many other shipments when the temperature is not kept at a sufficiently low degree, and it will be obvious that the ventilation should be adequate to take care of all contingencies but at the same time the car must be burglar proof. In cutting ventilating openings in the metal sections of bulkheads by the usual method of punching holes, it is impracticable to make very large holes or very many of them in the metal sections without materially weakening the bulkhead by the removal of metal so that it cannot be burglar proof.

One of the objects of my invention is the elimination of the foregoing difficulties by the provision of a refrigerator car bulkhead section which is burglar proof and which provides a maximum of ventilating area in said sections without removing metal from the sections or diminishing the strength of these metal members.

Another object of my invention is the provision of a novel bulkhead construction for refrigerator cars which is light in weight, rigid and burglar proof, economically manufactured, and which permits a maximum area of ventilating passages through said bulkhead.

Another object of my invention is the provision of a novel method of manufacture for ventilating openings of the class described.

Other objects and advantages of my invention will appear more fully from the following description and from the accompanying drawings, in which similar characters of reference indicate similar parts throughout the several views.

Referring to the drawings:

Fig. 1 is a cross sectional elevational view taken lengthwise through a refrigerator car, showing the ice compartment in one end of said car.

Fig. 2 is an elevational view in partial cross section taken on the line 2—2, showing the bulkhead construction. 55

Fig. 3 is an enlarged, detailed cross sectional view of the metal bulkhead section taken on the lines 3—3 of Fig. 2. 60

Fig. 4 is an enlarged, detailed cross sectional view taken on the line 4—4 of Fig. 3.

Referring to Fig. 1, 10 indicates in its entirety the refrigerator car, and 11 indicates in its entirety the bulkhead in one end of the refrigerator car, forming therein an ice compartment 12. The ice compartment 12 is provided in its ceiling with a hatchway 13 having a closure 14, and the interior of the ice compartment 12 is ordinarily readily accessible to anyone by lifting the cover 14 to open the hatchway 13. 65

The bulkhead 11 comprises a plurality of channelled sheet metal sections 15 which are fixed to the floor, ceiling and walls of the car in such manner that none of the fastening bolts or parts are accessible from the ice compartment 12, in order to make the main portion of the refrigerator car burglar proof. 70

In order to provide a bulkhead of substantial strength which is burglar proof, the metal sections are preferably made of the cross section shown in Fig. 3, each edge of the bulkhead section 15 having a backwardly extending flange 16, a parallel flange 17 and a flange 18 at right angles to the bulkhead. 75

The central part or web 19 of the channelled sections 15 may be extended at its upper end and bent at right angles to form a flange 20 for the purpose of fixing the upper end of the bulkhead sections to the ceiling of the car, and at the lower end of the bulkhead sections 15 the web may be removed from the point 21 down to the base of the sections 15, thereby providing a plurality of channelled legs 22 between which there is adequate space for the passage of air from the refrigerator car to the lower part of the ice compartment 12. 80

The ends and sides of the ice compartment 12 may be lined with metal plate as at 23, and the base of the ice compartment may have its floor covered with a layer of metal plate 24, the metal plate being preferably formed with a channelled edge 25, consisting of an upwardly extending flange 26, a sloping flange 27, and a downwardly extending flange 28. The channel 25 may thus be 85

100

105

adapted to receive a sill 29 which is fixed to the floor of the car, and the lower end of the bulkhead sections 15 may be supported upon said sill and channel by a plurality of shoes 30 comprising pressed metal members having an upwardly extending flange 31, a foot or laterally extending flange 32, downwardly extending flanges 33 on both sides of the channel 25, and an affixing flange 34 through which the bolts 35 may be passed to fix said shoes to the channelled legs 22 of the metal bulkhead sections.

The ice compartment 12 may be provided with an ice grating 36 which is removably supported between a pair of channelled members 37, the separate sections of grating 36 being locked in place by locking one of the sections 38 with a hook member 39 passing about a pin 40 and fixed by a bolt 41 underneath the grating. The ice grating 36 comprises a plurality of metal members having air spaces between the same which are adapted to support the ice and at the same time permit circulation of the air about the same through the apertures between the grating.

The complete details of this ice compartment construction are disclosed in my pending application, Serial No. 86,714, filed February 8, 1926, for grating construction of ice compartments of refrigerator cars, and the exact details of the ice compartment construction are not important except as they co-operate with the features of the present invention. It is, however, essential that the details of the ice compartment be such that the grating and other parts of the ice compartment are burglar proof, and that adequate provision be made for the passage of air into the ice compartment at the base thereof between the legs 22 and the ice grating 36.

The metal bulkhead sections 15 are customarily covered from the point 21 above the legs 22 to a point 42 below the upper ventilating openings 43, with a wall of transverse boards 44, which may be bolted or otherwise affixed to the flanges 17 of the metal sections, thereby covering the rear side of the bulkhead sections 15 and presenting a uniform wall surface on the bulkhead with the exception of the top and bottom thereof which is uncovered for the purpose of providing ventilating openings.

In the operation of the refrigerator car, a circulation of air is established by convection currents, the air in the ice compartment being cooled, and passing to the bottom of the car, whereupon air from the refrigerator car proper passes in at the ventilating openings 43 and the air from the ice compartment passes out between the legs 22 of the bulkhead. It will be observed that as most refrigerator cars depend for their air circulation upon this simple method of natural convection currents, it is highly important that a sufficient area of ventilating openings be

provided so that there is a minimum resistance to the flow of the air through the bulkhead and ice compartment.

This area of ventilating openings is adequately supplied at the base of the bulkhead 70 by removing the web of the metal sections 15 between the legs 22, the interior of the refrigerator car still being inaccessible to burglars from the ice compartment by reason of the ice grating 36. At the upper end of the 75 metal bulkhead sections 15, however, it is found that a maximum of ventilating area cannot be secured by the usual method of punching holes in the web 19 without weakening the metal sections 15 by the removal 80 of metal therefrom, and my invention contemplates the provision of ventilating openings in the metal sections 15 without weakening these sections by the removal of metal, but on the contrary actually strengthening 85 the same by the provision of a plurality of flanges extending at right angles to the web 19 of the metal sections 15.

In order to accomplish this result the metal sections 15 may be subjected to the following process of providing ventilating openings. The sections 15 are provided with a plurality of longitudinal slits extending from the point 42, which is the top of the wooden bulkhead wall 44, to a point 45 slightly spaced from the upper flange 20. While these slits may be made in other directions, they are preferably vertical so that the ventilating openings formed thereby may not present flat horizontal surfaces capable of accumulating dust 95 or other matter, and the slits above mentioned are made at regularly spaced intervals 46 extending completely across the web of the metal section 15.

The strips of metal 47 lying between the slits 46 are then bent at right angles to the plane of the web 19, as shown in Figs. 3 and 4, the major portion of the bend being located at each end 48 of the strips 47. The distance between the slits 46 should preferably be such that the strips 47 will be spaced a distance through which the hand or wrist cannot be passed, but this spacing may be varied considerably, depending on the nature of the conditions in each case.

The ventilating openings thus formed without removing any metal from the bulkhead section 15, provide a maximum area of ventilation, comprising the space between the outermost slits, reduced only by the thickness of the respective metal strips 47, which latter quantity is negligible. The burglar proof qualities of the bulkhead are actually increased by forming ventilating openings in this manner, as the metal strips 47 act in a measure like the flanges 16, 17 and 18 of the channelled section 15, reinforcing the metal sections in a longitudinal direction, and it is sufficient to provide ventilating openings 115 such as have just been described without any 120

bracing or reinforcing means. Where the slits 46 are of great length, or wherever it is desirable for other reasons to reinforce the same, this may be accomplished by providing 5 a transverse strip of strap steel 48 which is corrugated, as shown in Fig. 3, with a plurality of ridges 49 and valleys 50, thereby forming a plurality of grooves 51 which are so located that when the strap 48 is fixed 10 upon the metal section 15, the strips 47 have their edges in the grooves 51, being reinforced thereby so that they cannot be bent in a lateral direction to force the strips 47 apart. If desired, the strap 48 may pass across 15 the edges of the strips 47 on one side of the metal section 15, but I prefer to form the strap 48 so that half of the strips 47 have one edge in the grooves 51, while the balance of the strips 47 have their opposite edge in 20 the grooves 51. The strap 48 thus has a number of corrugated grooves 51 formed in it, corresponding to half the number of the strips 47, after which the strap 48 passes diagonally to the other side of the metal section 15, having a plurality of corrugated 25 grooves 51 formed to cooperate with the opposite edges of the remainder of the strips 47. It will thus be observed that when the strap 48 is riveted to the metal section 15 at each 30 end, as at 53, it is impossible to bend the strap 48 away from the edges of the strips 47 sufficiently to defeat its purpose, both ends of the strap 48 being firmly held against the strips 47 by the diagonal portion 52.

35 It will thus be observed that I have invented a method of forming ventilating openings in metal bulkhead sections which provides a maximum degree of ventilating area without weakening said metal sections by 40 the removal of metal therefrom, and that in so providing a maximum ventilating area I have retained all of the burglar proof qualities of the refrigerator car and ice compartment disclosed in my prior application above mentioned. My method of forming ventilating 45 openings or burglar proof grilles is capable of many other applications, and I do not desire to be limited to the precise application of this method shown in the present instance.

50 While I have illustrated and described the specific embodiment of my invention, many modifications may be made without departing from the spirit of the invention, and I do not wish to be limited to the precise details 55 of construction set forth, but desire to avail myself of all changes within the scope of the appended claims.

Having thus described my invention, what I claim as new and desire to secure by Letters 60 Patent of the United States is:

1. In a refrigerator car, a ventilating wall comprising a plurality of channelled metal sections having a plurality of spaced parallel slits in their webs with substantially all of the metal strips between said slits bent at right

angles to said web to form a ventilating grille.

2. In a refrigerator car, a ventilating wall comprising a plurality of channelled metal sections having a plurality of spaced parallel slits in their webs with substantially all of the metal strips between said slits bent at right angles to said web to form a ventilating grille, and means for bracing said metal strips.

3. In a refrigerator car, a ventilating wall comprising a plurality of channelled metal sections having a plurality of spaced parallel slits in their webs with substantially all of the metal strips between said slits bent at right angles to said web to form a ventilating grille, and means for bracing said metal strips comprising metal bands riveted to said channelled members in transverse relation to said strips and in holding engagement with each strip.

4. In a refrigerator car, a ventilating wall comprising a plurality of channelled metal sections having a plurality of spaced parallel slits in their webs with substantially all of the metal strips between said slits bent at right angles to said web to form a ventilating grille and means for bracing said metal strips comprising corrugated metal bands riveted to said channelled members in transverse relation to said strips with said strips held in the grooves of said corrugated band.

5. A metal bulkhead section comprising a metal plate having a flange extending at right angles across its upper edge, a channelled vertical flange at each of its lateral edges, said plate being cut away at its bottom between said channelled flanges to form a ventilating opening, and said plate having a plurality of spaced, parallel slits at its upper end with the strips between said slits twisted at each end with their major portions bent at right angles to said plate.

6. A metal bulkhead section comprising a metal plate having a flange extending at right angles across its upper edge, a channelled vertical flange at each of its lateral edges, said plate being cut away at its bottom between said channelled flanges to form a ventilating opening, and said plate having a plurality of spaced, parallel slits at its upper end with the strips between said slits twisted at each end with their major portions bent at right angles to said plate, and means for bracing said strips.

7. A metal bulkhead section comprising a metal plate having a flange extending at right angles across its upper edge, a channelled vertical flange at each of its lateral edges, said plate being cut away at its bottom between said channelled flanges to form a ventilating opening, and said plate having a plurality of spaced, parallel slits at its upper end with the strips between said slits twisted at each end with their major portions bent at right angles to said plate, and means for bracing said strips comprising metal bands riveted to said channelled members in trans-

verse relation to said strips and in holding engagement with each strip.

8. A metal bulkhead section comprising a metal plate having a flange extending at right angles across its upper edge, a channelled vertical flange at each of its lateral edges, said plate being cut away at its bottom between said channelled flanges to form a ventilating opening, and said plate having a plurality of spaced, parallel slits at its upper end with the strips between said slits twisted at each end with their major portions bent at right angles to said plate, and means for bracing said strips comprising a corrugated metal band riveted to said channelled members in transverse relation to said strips with said strips held in the grooves of said corrugated band.

9. In a refrigerator car, the combination of a car with a bulkhead in one end thereof, said bulkhead comprising a plurality of metal sections having legs at their bases with ventilating openings between said legs, an ice grating supported above said openings, said grating being locked from the interior

of said car, said sections having their upper wall portions slit and bent at right angles between said slits to form a burglar proof grille.

10. A method of forming ventilating openings in a metal wall part of a refrigerator car comprising slitting said metal wall part with a plurality of equally spaced parallel slits, and twisting the metal between said slits so that the major part thereof extends at substantially right angles to the plane of said metal wall part, forming a grille integral with said wall part.

11. In a refrigerator car, a bulkhead section comprising a channelled sheet metal member having channels formed at each of its lateral edges, said bulkhead section also being provided with ventilating openings comprising a plurality of spaced parallel slits with substantially all of the metal strips between said slits extending at right angles to the main body of said bulkhead section.

In witness whereof, I hereunto subscribe my name this 9th day of March, 1927.

GEORGE A. HULL.
